UNITED STATES PATENT OFFICE.

MICHAEL KOTUN, OF NEW GENEVA, PENNSYLVANIA.

COLLAPSIBLE TABLE AND CHAIR.

Application filed March 30, 1922. Serial No. 548,213.

To all whom it may concern:

Be it known that I, MICHAEL KOTUN, a citizen of Czecho-Slovakia, residing at New Geneva, in the county of Fayette and State 5 of Pennsylvania, have invented certain new and useful Improvements in Collapsible Tables and Chairs, of which the following is a specification.

The present invention consists of a collapsible table and chair and is designed as an improvement over my United States Letters Patent Number 1,380,153 patented May 31, 1921.

Objects of the present invention are to 15 provide a combined table and chair, or series of chairs, all of which may be conveniently folded so as to adapt the same for use by automobilists, campers or the like; to provide a collapsible table and chair 20 which may be quickly set up for use and expeditiously collapsed at the option of the user; to provide a collapsible table and chair characterized by a maximum rigidity; to provide a relatively rigid table top; and 25 to provide a device of this character which may be manufactured at a relatively small cost.

The above and other objects of this invention will be more fully understood from 30 the following description of the present preferred form of the invention taken in connection with the accompanying drawings wherein:—

Fig. 1 is a vertical sectional view of a device constructed in accordance with this invention showing the table and chair set up;

Fig. 2 is a fragmentary plan view of a table top constructed in accordance with this invention;

Fig. 3 is a vertical sectional view of the device in folded position showing the chair removed therefrom;

Fig. 4 is a detail fragmentary perspective view of one of the table supporting arms 45 and bracing strut showing the same disengaged;

Fig. 5 is a fragmentary perspective view of the invention showing the table in elevated position, in its containing section, the 50 table top being shown folded.

Fig. 6 is a top plan view of the device with the table top removed to disclose details; and

Fig. 7 is a plan view of the table top containing section showing its supporting ring 55 associated therewith.

The device of this invention consists of a main or outer supporting section 8 preferably made of metal and of cylindrical configuration. One end of this section is 60 closed, as indicated at 9, and the opposite end open. The open end is equipped with a cap or closure 10 which may also be used in the capacity of a drinking cup or cooking utensil. The section 8 has a slot 11 formed 65 therein and extending vertically therethrough. The lower end of this slot terminates short of the closed end 9 of this section while the other end terminates approximately midway the ends of the section 70 in a right angled slot 12.

Telescopically mounted within the main section 8 is an auxiliary section 13 which serves in the capacity of a table top containing tube and is preferably of cylindrical 75 configuration and relatively smaller than the main section 8 so that the outer periphery of the auxiliary section will be spaced from the inner periphery of the main section 8. One end of the auxiliary 80 section is closed as indicated at 14 while the opposite end is open. The lower closed end of said auxiliary section has an eye 15 formed thereon in which a split holding ring 16 is mounted. One terminal of 85 this ring is turned outwardly at right angles to provide a finger piece 17. This is used for elevating the auxiliary section 13 in the main section 8 and is engageable in the right angled portion 12 of the slot 11 in order to 90 support the auxiliary section in the desired position of elevation in the main section.

A coil spring 18 is mounted on the closed end 14 of the auxiliary section 13 and has superimposed thereon a core 19. This core 95 is preferably of tubular configuration and is equipped with an insertable lock 20 which carries a plurality of pivotally mounted arms 21 which constitute supporting members for a flexible table top per se 22. Each 100

of said arms 21 is preferably formed from a metal sheet having one end thereof pivotally engaged with the insert 20. Upon reference to Fig. 1 of the drawings, it will be noted that the block 20 is arranged beneath the closed upper end of the core 19, openings 23 being provided through which said arms extend. Each arm has the lateral margins thereof bent inwardly at right angles to provide a way 24 as shown to advantage in Fig. 4. This way in each arm is equipped with a spring 25. The outer terminal of each arm is bent at right angles as indicated at 26, and is engaged in any suitable manner with the table top per se 22, the margin of the latter preferably depending below the free margins of the right angled portions 26, as shown in Fig. 1.

Slidably mounted on the auxiliary section 13 is a collar 27 which has rising upwardly therefrom hinged struts 28 the outer end of each of which latter has right angled pintles 29 formed thereon. The pintles of each arm are reciprocally mounted in the way 24 of one of the arms and is normally urged outwardly toward the right angled end 26 of its arm by the spring 25. These struts will augment retention of the table top in an open or set up position.

30 In order to add to the rigidity of the table top 22, suitable supporting ribs 30 are provided. These ribs have the ends thereof pivotally connected to the arms 21. A pair of these ribs is arranged between each pair 35 of arms and has the proximate ends thereof pivotally connected as indicated at 31. Movement of these ribs is limited by an extension 32 formed on one of the ribs and overlapping the proximate end of the adjacent rib at the pivot point 31 thereof. These ribs, when set up force the arms 21 apart with obvious results.

When it is desired to set up the table the cap 10 is removed and the auxiliary section 13 elevated through the instrumentality of the finger piece 17 in a manner heretofore described. After said section has been elevated in this manner, a hasp 33, which is carried by one of the arms, and 45 engaged with openings 33' in the section 13, is disengaged. This permits the spring 18, which has been heretofore under compression, to expand with the result that the core 19 is projected upwardly in the auxiliary section 13. Upward movement of the core is limited in view of lugs 34 which are formed by bending portions of the upper terminal of the auxiliary section inwardly at right angles to overhang the core 19.

50 An annulus 35 is slidably mounted on the outer periphery of the main section 8 and has pivotally mounted thereon one end of each of a series of supporting legs 36. The opposite ends of these legs are bent at right angles to provide feet 37 for engagement

with the ground or other supporting body. If desired each of said legs may be provided with a loop, such as the loop 37 shown on one of the legs in Fig. 1, through which a seat supporting standard 38 is slidably mounted. The lower end of the standard is preferably pivotally mounted adjacent the closed end of the main section 8 while the opposite end terminates in furcations 39. These furcations are joined by a cross bar 40 which is pivotally mounted beneath a plate 41. The plate 41 has a run way 42 formed therein in which one end of a pedestal 43 is slidably mounted. The opposite end of said pedestal is engageable with the ground or other supporting object. The pedestal 43 extends between the furcations 39 and are pivotally connected thereto. A seat 44 is carried by the plate 41 and may be of any desired size or configuration and constructed of wood, metal or any other suitable material. In order to prevent displacement of the seat structure a retaining rod 45 is provided, one end of which is bifurcated, as indicated at 46 and pivotally associated with the annulus 35. The opposite end of said rod is bent at right angles, as indicated at 47, and engaged in the vertex of the furcations 39.

The seat structure may be collapsed by first disengaging the retaining rod 45 from the furcations 39 following which the annulus 35 is moved upwardly on the section 8 and the upper end of the pedestal 43 permitted to slide outwardly to the end of the run way 42 after which the seat 44 gravitates downwardly. The entire seat structure may in this way be folded flat against the outer periphery of the main section 8.

Although I have above described what now seems to be the preferred form of my invention it is nevertheless to be understood that various changes may be made therein especially in the details of construction, proportion and arrangement of parts within the scope of the claims hereto appended. By preference, however, the device is made relatively small and of cylindrical configuration so as to permit storage of same beneath an automobile seat or in any other relatively small compartment.

What is claimed is:—

1. A device as specified including a main supporting section equipped with a telescopic table top containing section, a hasp carried near the margin of the table top and engaged with its containing section, near the upper terminal of the latter, to normally hold the table top within said containing section and means to automatically elevate the table top when said hasp is released.

2. A device as specified including a main supporting section equipped with a telescopic table top containing section, means to

normally hold the table top within its section, means to automatically elevate the top when the first mentioned means is released, and lugs formed on the upper terminal of said table top section to limit upward movement of said table top.

3. A device of the character described including telescoping cylindrical sections one of which is equipped with a spring pressed

table top, arms carried by said table top 10 and equipped with springs, and struts pivotally carried by one of said sections and movable in said arms under influence of the springs to hold said table top in a rigid position.

15

In testimony whereof I affix my name.

MICHAEL KOTUN.
